UNITED STATES PATENT OFFICE

2,425,505

TWO-LEVEL REFRIGERATOR

John H. Benson, Salem, Ohio, assignor to Mullins Manufacturing Corporation, Salem, Ohio, a corporation of New York

Application November 18, 1944, Serial No. 564,129

6 Claims. (Cl. 312—161)

1

This invention relates to a refrigerator cabinet construction. Basically the invention contemplates an open top refrigerator cabinet having two top levels and two temperature levels.

It is an object of the present invention to provide openings which are separately accessible and provide a top construction which is readily adapted for table use in a domestic kitchen.

In the drawings:

Fig. 1 is a perspective view of the cabinet showing one closure member in open position.

Fig. 2 is a partial end elevation showing the tops closed.

Fig. 3 shows a third position in which the back top member is swung forward for work table use.

Fig. 4 is an end elevation showing the position similar to that of Fig. 1.

Fig. 5 shows the insulating closure member of rear compartment in open position.

Fig. 6 is a vertical section.

Fig. 7 is a plan view showing the storage baskets in the front compartment.

In Fig. 1 the cabinet is shown generally at 20 with a closure member 21 to cover the compressor compartment and two drawers 22 and 23 for vegetable storage and the like. The cabinet rests on a base 24. The top of the cabinet has a portion at level 25 and another portion at level 26. These two portions are separated by a wall 27 between a front storage compartment 28 and a back storage compartment 29. There are two closure members for the back storage compartment. One is shown at 30 and is a hinged and recessed type of closure member. The other member is shown at 31 resting across the top of the member 30 and hinged at a point 32 to an L-shaped closure member 33 which serves as a top for the front compartment. In the front compartment baskets 40 slide at two levels 41 and 42. The back compartment may be used as a deep freeze unit having temperatures below 32° F. while the front compartment may be maintained at 35° to 42° for normal food storage. The bottom of the closure member 31 is intended to be a work surface and can be made of abrasion resistant material such as hard wood or other material which may be used for cutting in the same manner as a bread board is now used. When this surface is desired, it is simply necessary to swing the top member 31 on its hinge 32 to the position shown in Figs. 3 or 5 where it becomes flush with the foot of member 33 to form a flat work table across the entire cabinet.

2

In the closed position shown in Figs. 2 and 6, the top presents an attractive appearance and renders the compartments of the cabinet readily accessible.

5 I claim:

1. In a refrigerator cabinet, upright walls including a partition defining a front and a back compartment, the compartments being open at the top at spaced levels, a primary closure member for the higher of said compartments arranged to lie flush with the top of the opening thereof, a panel adapted to serve as a closure member for the lower compartment and provided with an upward extension to the top level of the higher compartment, the extension abutting the partition, and a second panel hinged to said extension and adapted to serve as a secondary closure for the higher compartment, said second panel being movable on its hinges to a position resting within said first panel to provide a level top over the entire cabinet.

2. In a refrigerator cabinet, upright walls including a partition defining a front and a back compartment, the compartments being open at the top at spaced levels, a primary closure member for the higher of said compartments arranged to lie flush with the top of the opening thereof, a panel adapted to serve as a closure member for the lower compartment and provided with an extension to the top level of the other compartment abutting the partition between said compartments, and a second panel hinged to said extension and adapted to serve as a secondary closure for said other compartment, and a bread cutting surface on the bottom of said second panel, the latter being movable to a position resting within said first panel to provide a level working surface over the entire cabinet.

3. In a refrigerating cabinet, upright walls including a partition defining a front and a back compartment, the compartments being open at the top at spaced levels, the rear being higher than the front, an L-shaped closure for the front compartment having the foot of the L extending to the top of the rear compartment, and a cover member for the rear compartment hinged to the foot of the front closure and arranged to swing into resting relation within the front closure to provide a level working surface over the entire cabinet.

4. In a refrigerating cabinet, upright walls including a partition defining a front and a back compartment, the compartments being open at the top at spaced levels, the rear being higher than the front, a primary closure member for the

rear compartment the top of which is flush with the top of the cabinet, an L-shaped closure for the front compartment having the foot of the L extending to the top of the rear compartment, and a secondary closure for the rear compartment hinged to the foot of the front closure member and arranged to swing into resting relation within the front closure to provide a level working surface over the entire cabinet, said secondary closure having an abrasion resistant work surface on the bottom.

5 In a refrigerator cabinet, upright walls including a partition defining two adjacent compartments, the compartments being open at the top at different levels, and a single closure means consisting of two members hinged together, one of which covers the higher compartment and the other of which covers the lower compartment, the member covering the lower compartment being L-shaped in cross section having the vertical portion of the L lying adjacent the partition and hinged to an edge of the other of said members which is provided with a bottom surface composed of a hard abrasion resistant material to serve as a work surface.

10

15

20

25

6. A two-level top refrigerator cabinet having separated compartments opening at the top at different levels, a separate closure means for the higher compartment, a flat panel for covering said higher compartment closure means, an L-shaped panel adapted as a closure for the lower compartment, the foot of the L extending upwardly to the edge of the higher compartment and being hinged to the flat panel adjacent said edge, said L-shaped closure panel serving as a shelf when swung over the flat cover panel, and the flat cover panel serving as a cutting board when swung over on the L-shaped panel.
